W. E. CARTER.
CONVERTIBLE PERAMBULATOR AND PUSH CHAIR.
APPLICATION FILED APR. 10, 1922.
1,423,912. Patented July 25, 1922.

UNITED STATES PATENT OFFICE.

WALLACE ERNEST CARTER, OF DOVER, ENGLAND.

CONVERTIBLE PERAMBULATOR AND PUSH CHAIR.

1,423,912.

Specification of Letters Patent. Patented July 25, 1922.

Application filed April 10, 1922. Serial No. 551,350.

To all whom it may concern:

Be it known that I, WALLACE ERNEST CARTER, a subject of the King of Great Britain and Ireland, and a resident of Dover, county of Kent, England, have invented a certain new and useful Improvement in Convertible Perambulators and Push Chairs, of which the following is a specification.

This invention relates to vehicles of the kind which are convertible to form either a perambulator or push chair, and employing a detachable fore end to allow of such conversion, with suitable means for securing to the main body.

15 The present invention is characterized in that the sides of the detachable fore end member partly overlap the sides of the main body when said detachable member is in position, and said detachable member is furnished with a seat which contacts on its underside with an upstanding portion of the main body. Further, an improved means is provided for securing the detachable part to the main body, consisting of a rod passing transversely through the lower part of the body, and catches at the upper part near the overlapping edges.

30 The invention will be readily understood by reference to the accompanying sheet of drawings which illustrate a practical embodiment, and wherein:

Figure 1 is a side elevation of the perambulator, showing the detachable portion in dotted lines.

35 Figure 2 is a plan of the perambulator, showing the detachable member in position.

Figure 3 is a side view of the detachable portion.

40 Referring to the drawings, *a* represents the fixed part of the body, and *b* the detachable member.

The sides *b'* of the detachable member fit externally over a portion of the sides *a'* of the body *a*, a catch *c* on each side of the body securing the detachable member *b* in position. Said catches and the interior of the sides *b'* of the detachable member are preferably padded with suitable material to prevent scratching the main body when affixing and removing the detachable member *b*. Additional security is provided by a rod *d* which passes transversely through the detachable member *b* and the body *a*, said rod being held in position by means of a nut

screwed thereon, a split pin, or other convenient means.

In order to facilitate fitting the rod, and finding the hole on the further side of the body, a tube *e* is provided under the floor of the body through which the rod *d* passes.

60 The seat *b²* of the detachable member is fixedly secured therein. The floor boards of the perambulator at the end remote from the handle extend upwardly for a suitable distance to provide a footrest for the occupant of the chair seat when the carriage is being used as a push chair. The top of said footrest contacts with the underside of the seat *b²* of the detachable member when the same is in position, suitable padding 65 means, such as rubber buffers, being incorporated, if necessary, to prevent scratching. If desired, grooves, slots or equivalents on the underside of the body *b²* may engage corresponding projections on the aforementioned footrest, or vice versa.

70 The portions of the sides *a'* which are exposed when the detachable member *b* is removed, may be shaped or curved to give the appearance of the usual type of push chair.

75 The springs, which are of the type usually fitted to push chairs, are secured to the body by means of straps and shackles, and a hood of the usual type is employed, that is, one comprising a number of arms pivoted 80 at or about the centre of the sides, said hood being merely swung about its pivots when the perambulator is converted, without necessitating its removal.

85 In addition, there may be employed, if desired, folding legs for negotiating steps, and to render the push chair absolutely safe from tipping, and a chain for locking the wheels to facilitate the operation of conversion when performed by one person.

90 I claim:

A convertible perambulator and push chair including in combination with the main body having a seat, a detachable foot section also having a seat adapted to rest on the front edge of the main body while the rearwardly projecting sides telescope within the main body, means for holding said detachable foot section in place consisting of catches including socketed parts carried 100 by the main body adjacent the upper front edge thereof and hook portions carried by the rear edges of the detachable foot section 105

and engaging with said socketed parts, and a transverse rod carried by the lower rear edge of the detachable foot section and adapted to engage beneath the main body, 5 the said catches and rod cooperating to prevent the seat in the said detachable section from rocking on the edge of the foot sec-

tion of the main body and becoming disengaged therefrom.

In testimony whereof I have affixed my 10 signature hereto this 22nd day of March 1922.

WALLACE ERNEST CARTER.
